SELF-DISPENSING PACKAGE

Walter E. Amberg, Beverly Shores, Ind., assignor
to Universal Paper Products Company, Chi-
cago, Ill., a corporation of Illinois

Application March 7, 1941, Serial No. 382,179

6 Claims. (Cl. 206—56)

This invention relates to a self-dispensing package for paper cups, more particularly to paper cups or other similar containers having a flanged, rolled or beaded rim.

The problem of providing a shipping container for paper cups, or similar articles having a rolled, flanged or beaded rim and which can be converted by the user into a dispenser for the paper cups, has presented some difficulties. One difficulty is that the bead or flange around the rim or mouth of the cup causes the cup to be relatively more rigid than a similar cup not having a bead or flange, and hence, does not permit the cup to flex as readily. Furthermore, the bead or flange when striking against fingers, projections or similar devices employed in dispensing cups, may become caught thereon and unrolled, thereby damaging the cup and increasing the resistance to its removal.

It will be realized that in dispensing cups the ease of removal of the cups from a stack thereof is rather important. At the same time it is still more important that the cups be removed from the stack not more than one at a time. If more than one cup is removed at a time the cups are wasted and the cost of providing them is increased. This is particularly important in railroads, offices and public places where thousands of cups are used in a relatively short period of time.

One of the objects of the present invention is to provide a self-dispensing package or carton which will dispense cups having a beaded rim from the bottom of a stack one at a time and without requiring a substantial amount of hand pull.

Another object of the invention is to provide a shipping carton in which paper cups or similar articles may be shipped without substantial exposure to dust and dirt and which at the same time can be easily converted to a self-dispensing package.

Other objects and advantages of the invention will be apparent by reference to the following description in conjunction with the accompanying drawing, in which:

Figure 1 represents the carton blank;

Figure 2 illustrates the lower portion of a shipping carton after it has been converted to a self-dispensing package in accordance with the present invention.

Referring to Figure 1, it will be seen that the carton blank illustrated is of an ordinary and well known type except for the triangular shaped cut or perforated areas 2, 4, 6 and 8. These

areas are defined either by cuts or partial cuts in the sides of the carton, or by perforations, and are so constructed that the base of each of the triangular areas can be pushed inwardly by pressing against the corner or edge of the carton. The preferred form of construction is to have the base of each triangular area 2, 4, 6 and 8 formed by a cut or line of severance extending entirely through the cardboard carton and to have the sides formed by cuts or lines of severance extending only partially through the cardboard carton. Thus, when pressure is exerted against the edge of the carton in any of the triangular areas 2, 4, 6 and 8 the base of the area will immediately be pressed inwardly to the position shown in Figure 2. As illustrated in Figure 2, each of the pressed in portions 2, 4, 6 and 8 forms a more or less pyramidal structure. This particular type of structure plus the fact that the sides of the triangular areas are partially cut from the outside, serves to keep the pressed in portions in shape. However, if desired they may readily be pressed out again.

With this type of structure the pressed in areas 2, 4, 6 and 8 are ordinarily not sufficiently rigid to support a stack of cups and to permit the cups to be dispensed from the bottom of the stack one at a time. In accordance with the present invention it has been found that the simple expedient of placing a rubber band 10 around the lower portions or bases of pyramidal pressed in portions 2, 4, 6 and 8 will make it possible to dispense paper cups or similar articles having a flanged or beaded rim from the bottom of a stack one at a time. As each cup is dispensed it will cause the pressed in areas 2, 4, 6 and 8 to give slightly in an outward direction, but the rubber band 10 causes them to immediately move inwardly again to engage the next succeeding cup and support the remainder of the stack. Thus, only one cup is dispensed at a time and no loss or waste is incurred due to faulty dispensing action of the package. Furthermore, the presence of the rubber band 10 prevents the pyramidal pressed in portions 2, 4, 6 and 8 from assuming their original positions in the corners of the carton when the cups are dispensed. It will be recognized, of course, that if this occurs the entire stack of cups would drop through the bottom of the carton.

The invention, as illustrated in the drawing, shows a cone-shaped cup having a rolled or beaded rim. As shown, this cup is in a position in which it is ready to be dispensed by a hand pull from the bottom of the package. The sides

of the cup are generally tapering or converging. The edges 14, 16, 18 and 20 of the pyramidal pressed in portions 2, 4, 6 and 8, respectively, are also generally tapering or converging and as the cup is withdrawn the beaded rim 12 slides downwardly along the inclined edges 14, 16, 18 and 20 of the dispensing elements 2, 4, 6 and 8. At the same time, these edges 14, 16, 18 and 20 are pressed outwardly due to the relative rigidity of the beaded rim 12. As soon as the beaded rim 12 of the cup is passed beyond the edges 14, 16, 18 and 20 in a downward direction, the rubber band 10 immediately causes these edges to be pressed inwardly again in order to engage the next succeeding cup and to support the stack of cups. One important feature of this arrangement is that the beaded rims of the cups are not distorted or broken. This is important because, as is well known, once a beaded rim is distorted it does not readily return to its original or undistorted shape. Naturally the user does not care to employ a distorted cup.

It will be recognized that certain modifications may be made in the structure described without departing from the invention. The self-dispensing package shown, although particularly valuable for dispensing cone-shaped paper cups having a beaded rim, may also be used for dispensing other types of cups having beaded rims such as flat bottom cups. The ears or flaps of the carton shown by the numerals 22, 24, 26 and 28 may be torn off or otherwise removed when the carton is converted to a self-dispensing package, thereby permitting the bottom of the lowermost cup to extend a substantial distance through the bottom of the package.

In describing the present invention, the pressed in portions, or areas, which assist in dispensing the cups have been referred to as being generally pyramidal in structure. It will naturally be observed that these areas when pressed in do not form a complete pyramid but rather what may be termed a semi, open-sided pyramid. It will be observed further that in the preferred structure illustrated in the drawing the triangular areas are substantially equilateral and are disposed at the corners of the carton at or near one end thereof. Additionally, it will be noted that the bases of the triangular areas are preferably in the same transverse plane, although they may be in different planes, and that the corners of the carton when pressed in serve to form one corner or edge of the pyramidal structure. As will be observed, the corners of the carton in the structure illustrated are substantially at right angles to the bases of the triangular areas, when the triangular areas are pressed in to form the generally pyramidal dispensing elements. It will further be noted that the corners of the carton are the supports for the lowermost cup of the stack. Since these corners or edges slant in a generally downward and inward direction, they offer very little resistance to the removal of the cups from the bottom of the stack by a hand pull. The resistance is further decreased by the angularity of the edges of the pressed in portions which permits contact with the cups only over a very narrow area. It will additionally be noted that the encircling rubber band in the preferred structure illustrated, presses against the outside of the generally pyramidal dispensing element at the junctures of the bases of these elements with the sides of the carton.

It will be understood that while it is preferable to use a rubber band 10, or other resilient

means, to keep the pressed in areas 2, 4, 6 and 8 from being snapped out when a cup is dispensed, another type of band such as a string or cord may be employed. If a relatively non-resilient means such as a cord or string is used, the flexibility or resiliency of the cardboard from which the members 2, 4, 6 and 8 are formed is still sufficient to permit the cups to be dispensed.

Having thus described the invention, what I claim as new and desire to secure by Letters Patent of the United States is:

1. A self-dispensing package for paper cups and similar articles having flanged or beaded rims, said package comprising a carton having a plurality of triangularly shaped areas formed in the side walls at the corners near one end thereof, said areas being defined at their bases by cuts and at their sides by hinge lines integral with the side walls of the carton enabling said areas to be pressed out of alignment with the walls of said carton to form constrictions in the end of said carton adapted to support the lowermost cup of a stack of cups adjacent its rim, said cuts being disposed at substantially the same distance from said end of said carton and resilient means held in position by said cuts and tending to hold said areas in the state which they assume when pressed out of alignment with the walls of said carton, whereby when the lowermost cup of the stack is dispensed said resilient means will permit the constrictions in the carton to yield and thereafter will tend to return them to their normal positions.

2. A self-dispensing package for paper cups and similar articles having flanged or beaded rims, said package comprising a carton with a plurality of areas pressed inwardly and adapted to support the lowermost cup of a stack of cups adjacent the rim thereof, said pressed in areas being substantially of an open-sided, semi-pyramidal form with the base of said pyramidal structure in contact with the lowermost cup of the stack, and resilient means pressing inwardly at the outer corners of said pyramidal structure and holding said pressed in areas against outward movement whereby when the lowermost cup of the stack is dispensed the rim thereof will tend to press said areas outwardly and said resilient means will tend to press them inwardly again after the cup has been dispensed.

3. A self-dispensing package for paper cups and similar articles having flanged or beaded rims, said package comprising a carton of polygonal cross-section having a plurality of triangularly shaped areas formed in the side walls at the corners near one end thereof, said areas being defined at their bases by cuts running transversely across the corners of said carton and at their sides by hinge lines integral with the side walls of the carton, enabling said areas to be pressed out of alignment with the walls of said carton to form constrictions therein adapted to support the lowermost cup of a stack of cups adjacent its rim, said cuts being disposed at substantially the same distance from one end of said carton and an elastic band disposed in said cuts and tending to hold said areas in the state which they assume when pressed out of alignment with the walls of said carton whereby when the lowermost cup of the stack is dispensed said elastic band will permit the constrictions in the carton to yield and thereafter will tend to return them to their normal positions.

4. A self-dispensing package for paper cups

and similar articles having flanged or beaded rims, said package comprising a carton with a plurality of areas pressed inwardly and adapted to support the lowermost cup of a stack of cups adjacent the rim thereof, said pressed in areas having substantially an open-sided, semi-pyramidal structure with the base of said pyramidal structure adapted to engage the lowermost cup of a stack of cups, and a rubber band encircling the outside of said carton at the juncture of said pyramidal pressed in portions with the sides of the carton whereby when the lowermost cup of the stack is dispensed the rim thereof will tend to press said pyramidal areas outwardly and said rubber band acting against the outer corners of the base of said pyramidal structures will tend to press them inwardly again after the cup has been dispensed.

5. A self-dispensing package for paper cups and similar articles having flanged or beaded rims, said package comprising a cardboard carton of substantially rectangular cross section having a plurality of substantially equilateral triangular areas near one end thereof, said triangular areas having their bases in substantially the same plane adjacent said end, having the corners of said carton substantially at right angles

thereto with the apexes of said triangular areas coinciding with the corners of said carton, the bases of said triangular areas being defined by a line of severance and the sides of said triangular areas being partially cut on the outside to facilitate the inward movement thereof whereby in the normal position of said triangular areas said package may be used as a shipping container and when said areas are pressed inwardly from the bases thereof they form generally pyramidal structures slanting in a downward and inward direction and act as dispensing means.

6. A self-dispensing package for paper cups, said package comprising a carton having angularly disposed walls and cup retaining members formed at the corners of said carton adjacent one end thereof, said cup retaining members having transverse slits extending into the adjacent side walls and upwardly converging scores extending from the ends of the slits substantially to the corners, the portions of the retaining members bounded by said slits and converging scores being deflected inwardly into triangular downwardly inclined cup retaining detents permitting the withdrawal of cups one by one.
